Attorney

UNITED STATES PATENT OFFICE.

GEORGE M. DWIGHT, OF OREGON, ILLINOIS.

SLED.

SPECIFICATION forming part of Letters Patent No. 339,747, dated April 13, 1886.

Application filed February 8, 1886 Serial No. 191,168. (No model.)

To all whom it may concern:

Be it known that I, GEORGE M. DWIGHT, a citizen of the United States, residing at Oregon, in the county of Ogle and State of Illinois, have invented certain new and useful Improvements in Sleighs or Sleds; and I do hereby declare that the following is a full, clear, and exact description of the same, reference being had to the annexed drawings, making a part of this specification, and to the letters and figures of reference marked thereon.

Figure 1 of the drawings is a perspective view of a sled embodying my invention; Fig. 2, a longitudinal section thereof; Fig. 3, a detail end view; and Fig. 4 a detail view in perspective of the front end of one of the runners.

The present invention has relation to certain new and useful improvements in sleighs and sleds; and it consists in the details of construction substantially as shown in the drawings, and hereinafter described and claimed.

In the accompanying drawings, A represents the usual fenders, and B the benches, of a sled. The runners C, I form of angle-iron, which are L shape in cross section, as shown, and to the under side of these runners are secured by bolts *a* and nuts *b* the shoes D of cast-iron or steel. The front end of the runners C is formed with an upright retaining flange, *c*, and horizontal inwardly projecting flange *d*, the former being mortised in and secured to the outer edge of the fenders A by rivets or bolts, and in like manner the latter-mentioned flange is securely fastened to the under side of the fender, bracing the runner at the point of attachment to the fender both in a lateral and vertical direction, the horizontal flange also forming a support for the end of the fender.

The most simple manner of forming the flanges *c* *d* is to slit the runner at the apex of the angle and bend the inner portion of the angle-iron inwardly and horizontally, the outer portion thereof projecting above and of a

length equal to the thickness of the fender to 45 which it is attached, and, if preferred, the two flanges thus made may be welded together. The knees E are bifurcated, as shown, the arms of the bifurcation being formed with laterally-extending flanges, *e*, by which they are 50 bolted to the under side of the benches B for supporting them. The lower end of the knees E are formed with an inwardly-extending chair, F, which is of greater width than the arms of the knee, to form a wide and extended 55 bearing or seat for the runners and brace them both horizontally and vertically, and are secured to the runners by bolts or rivets *f*, and the knee to the upright portion of the runner by bolts or rivets *g*.

The knee, with its flanges and chair, is formed in one piece by welding or otherwise, and provides a solid and firm support and brace for both the benches and runners of the sled. It will be noticed that the shoes D project below the runners C. Thereby no portion 65 of the runners is exposed to frictional wear.

Having now fully described my invention, what I claim as new, and desire to secure by Letters Patent, is—

In a sleigh or sled, the runners thereof formed of angle-iron, and bifurcated knees having laterally-extending flanges at their upper ends, and at their lower ends inwardly-extending chairs connected, respectively, to the 75 benches and runners, in combination with shoes attached to the under side of the runners and projected below the same to protect the entire under surface from frictional wear, substantially as and for the purpose set forth. 80

In testimony that I claim the above I have hereunto subscribed my name in the presence of two witnesses.

GEORGE M. DWIGHT.
